UNITED STATES PATENT OFFICE.

WILLIAM J. PAUL, OF PITTSBURGH, PENNSYLVANIA.

DESIGN FOR A VENDING-MACHINE CASE.

44,615.

Specification for Design.

Patented Sept. 2, 1913.

Application filed April 17, 1913. Serial No. 761,850. Term of patent 7 years.

To all whom it may concern:

Be it known that I, WILLIAM J. PAUL, a citizen of the United States, residing at Pittsburgh, in the county of Allegheny and State of Pennsylvania, have invented a new, original, and ornamental Design for Vending-Machine Cases, of which the following is a specification, reference being had to the accompanying drawing, forming part thereof.

The figure is a perspective view of a vending machine case, showing my new design.

I claim:

The ornamental design for a vending machine case, as shown.

WILLIAM J. PAUL.
